GRAIN GUIDE AND RETARDER FOR
BINDERSChristian M. Kvols, Hawarden, and Frank Vogel-
zang, Chatsworth, Iowa

Application October 20, 1939, Serial No. 300,410

5 Claims. (Cl. 56—472)

Our invention relates to a binder improvement.

An object of our invention is to provide an attachment attachable to a binder deck which will automatically deflect the cut grain to a strictly 5 lateral position with respect to the packing arms, needle arms, and other parts of the binding arrangement which forms the bundles.

A further object of our invention is to provide an attachment which will automatically deflect 10 either short or long grain stalks uniformly so that all of the grain will be positioned laterally with respect to the binding arrangement so that there will be no waste of grain which otherwise, in travelling forwardly through the arrangement, 15 would be lost.

A further object of our invention is to provide a series of deflecting arms of varied heights which arms are spring urged to accommodate varying masses of grain.

20 A further object of our invention is to provide an attachment which can be readily accommodated to standard binders and which is so arranged to cooperatively work with the needle and packer arrangement in an efficient and uniform 25 manner.

A further object of our invention is to provide all of the foregoing features in a simple construction.

30 With these and other objects in view, our invention consists in the construction, arrangement and combination of the various parts of our device, whereby the objects contemplated are attained, as hereinafter more fully set forth, pointed out in our claims, and illustrated in the accompanying drawing, in which:

Figure 1 is a sectional view taken substantially along the lines 1—1 of Figure 2,

Figure 2 is a plan view taken just beneath the deflector deck.

40 Figure 3 is a sectional view taken substantially along the lines 3—3 of Figure 2, and

Figure 4 is an enlarged detail.

In the usual construction of binders the grain 45 is first cut by the sickle which then falls on the horizontal belt and is carried upwardly through a pair of belts to the deck and the binding mechanism. Considerable difficulty is experienced in maintaining the grain stalks in a strictly transverse or lateral position throughout the process, and as a result a portion of the grain travels either forwardly or angularly with respect to the lateral position. Due to this fact, the bundle tying portions of the binder will not receive certain portions of the stalks since they are traveling

substantially forwardly, and as a result, a fairly high percentage of the grain is lost.

The principal objective of our invention is to take the grain which rises to the binding platform and to straighten the grain stalks so that they lie strictly in a lateral position and so that the bundles will thereby be formed without any waste, and are more uniform.

We have used the character 10 to designate the upper angularly positioned conveyor belt which 10 travels over the roller 11 and the character 12 to represent the lower belt positioned adjacently thereto which travels over the roller 13. The conveying slats are indicated by the character 14. The grain travels between these belts or at 15 and 15 which belts communicate with the lower horizontal belt adjacent the sickle. The idler roller is indicated by the character 16, and the upper deflector deck by the character 17.

The function of our arrangement is to take 20 the grain which is elevated by means of the belts 10 and 12 and which passes over the roller 16 and to deflect it to a transverse position. To accomplish this result we provide the device which will now be described and which comprises essentially 25 a flat lengthened supporting bar 18 which is suitably attached by bolting, as explained later herein to the deck 17 of the binder and just above the butt adjustor 19 which adjustor travels on the vertical rolls 20. Attached to the lengthened bar 30 18 are a series of flexible spring steel arms 21, 22, 23, 24, 25, 26, 27, and 28 which are all attached at 29 to the aforesaid bar 18. Each of these flat spring members include the arcuate bowed portions 30 (see Fig. 4) which terminate in the 35 slightly upturned lips 31. The first three members adjacent the butt adjuster 19, or the members 21, 22, and 23, are spaced close together as shown, and the further members are spaced farther apart. The members 21, 22 and 23 are 40 also progressively longer horizontally as well as downwardly and, as shown in Fig. 3, all of these flat spring steel members project downwardly from the member 18.

The member 24 also projects to a greater distance forwardly and downwardly and the member 25 is correspondingly longer than the member 24 and projects forwardly and downwardly to a greater extent. The member 26, however, is shorter than the member 25, and the last member 50 28 is shorter than the member 27 forwardly as well as downwardly. In other words, in considering the first five spring members, it will be noted that, taken from the top of Fig. 2, they are progressively longer in both directions, and in 55

considering the last three members 26, 27, and 28 the lengths diminish correspondingly. It will be specifically noted that all of the flat steel members are positioned angularly with respect to the bar 18, but it will also be noted that the bowed portions 30 are so bent that the planes of the bowed portions 30 are all substantially parallel to the bar 18.

The needle which is attached to the usual shaft 10 is indicated by the character 32 and the packer points by the character 33 and the packer heel by the character 34, the approximate position of the same being as shown in Figures 1 and 2 with the usual slots provided in the deck 35 for accommodating the same, with the further slots for the other packer arms also being shown. The bar 18 being of simple structure is also provided so that it can be accommodated to any grain binder of any type.

Now that the structure of the device has been explained, we will explain the operation thereof. It will be noted that the grain stalks travelling upwardly between the belts 10 and 12, and more particularly those stalks which are more forwardly inclined, will travel in a forwardly inclined position with respect to the packer. The butt adjustor 19 carries the butt ends of the stalks forwardly, and the spring arms 21, 22, 23, 24, 25, 26, 27, and 28 will tend to straighten out these stalks to a strictly transverse position parallel to the bar 18 since the end of the stalks will be striking against the downwardly bowed portions 30. The shorter arms 21, 22, and 23 will straighten out the short grain stalks and due to the fact that these arms are close together, they will prevent passage of grain portions between the same. The longer arms such as 24 and 25 will retard the forward ends of the longer stalks thereby straightening them in the same manner, and as the butt adjustor travels forwardly, the tendency will be to straighten out the stalks to a strictly lateral position so that they can be picked up by the packer arms and heels and convey the material in a transverse position to the binding arrangement. The packer arrangements are positioned as shown so that the effect is most efficient.

From examination of Figure 3 it will be noted that the projection downwardly of the bowed portions 30 also insures that the longer material is straightened out and carried downwardly directly onto the packer conveying arrangements. The spring arms 26, 27, and 28 also serve an important function when the binder is travelling uphill, the normal direction of the binder being indicated by the character 36. When the machine is travelling uphill, the arms 26, 27, and 28 will then be at the lowest point of the arrangement. If these arms were not provided, there would be a tendency for the material to slip past the arm 25, thereby resulting in waste of the stalks of grain which would then slip past the packing arrangements. Due to the diminishing lengths, however, of these arms, the material is restricted and brought back to a lateral position as desired, with the diminishing depths of the arms taking care of the material in the same manner. The construction of the various arms being of flat spring steel, permits any amount of grain to be accommodated, since they can bend upwardly for greater quantities and in this manner the arrangement will provide a resilient effect for this purpose.

For providing further adjustment of the bar 18 we provide the pair of flat members 37 which are attached to the bar 18, which members 37 include the slots 38, a portion of which slots run into the

bar 18 itself and which slots extend forwardly a substantial distance. If desired, the entire arrangement can be supported by means of the bolts such as 39 which are attached through the slots 38 and through the deflector deck 17. These slots 5 will permit forward or rearward positioning of the bar 18, thereby carrying the various arms forwardly or rearwardly to any desired position, and also these slots provide the additional feature of inclining the bar 18 angularly with respect 10 to the transverse position. This feature will accommodate the arms for different speeds and for various other purposes requiring adjustment, such as different types of grain, etc., since the positioning of the arms further outwardly will accommodate different quantities of grain as well as providing an adjustment for different speed ratios to prevent undue accumulation. The swinging of the arm angularly will also provide additional adjustable features so that the arms can be 20 thus positioned to retard the grain at either end desired.

It will now be seen that we have provided an attachment which is attachable to any grain binder deck which will automatically deflect the cut 25 grain stalks to a strictly lateral position with respect to the binding portions of the binder, that we have provided means for eliminating waste of grain which would otherwise tend to travel forwardly along the packer deck, that we have provided means for moving shorter stalks to a lateral position, and that we have provided a simple structure involving the use of only one unit member for these purposes.

Some changes may be made in the construction and arrangement of the parts of of our invention without departing from the real spirit and purpose of our invention, and it is our intention to cover by our claims any modified forms of structure or use of mechanical equivalents which 40 may be reasonably included within their scope.

We claim as our invention:

1. In combination with a binder, an upper deflector deck, a lateral bar attached thereto, a plurality of spaced flat arms attached to said bar, said 45 arms having downwardly positioned extensions, and said arms being positioned above a binder deck, said arms being slightly inclined from a position transverse to the bar, each successive adjacent arm being of increasing length with respect to the arm preceding it forwardly and downwardly, to a point substantially at the mid-point of said bar, each successive adjacent arm thence being of decreasing length with respect to the arm preceding it beyond said mid-point. 55

2. In combination with a binder, an upper deflector deck, a lateral bar attached thereto, a plurality of spaced flat arms attached to said bar, said arms having downwardly positioned extensions, and said arms being positioned above a binder 60 deck, said arms being slightly inclined from a position transverse to the bar, each successive adjacent arm being of increasing length with respect to the arm preceding it forwardly and downwardly, to a point substantially at the mid-point of said bar, each successive adjacent arm thence being of decreasing length with respect to the arm preceding it beyond said mid-point, a limited group of said arms at one end of said bar being closely spaced together, the further of said 70 arms being spaced a substantial distance apart.

3. In combination with a binder, an upper deflector deck, a lateral bar attached thereto, a plurality of spaced flat arms attached to said bar, said arms having downwardly positioned extensions, 75

- and said arms being positioned above a binder deck, said arms being slightly inclined from a position transverse to the bar, each successive adjacent arm being of increasing length with respect to the arm preceding it forwardly and downwardly, to a point substantially at the mid-point of said bar, each successive adjacent arm thence being of decreasing length with respect to the arm preceding it beyond said mid-point, a limited group of said arms at one end of said bar being closely spaced together, the further of said arms being spaced a substantial distance apart, said downwardly positioned extensions being substantially of an arcuate configuration and having their planes substantially parallel to said bar, an adjusting member comprising a pair of attaching members having lengthened slots therein, means for attaching bolts through said slots to attach said lateral bar in selected adjustable position to the upper deflector deck of the binder. 5
- 10 4. In combination with a binder, an upper deflector deck, a lateral bar attached thereto, a plurality of spaced flat arms attached to said bar, said arms having downwardly positioned extensions, and said arms being positioned above a binder deck, said arms being slightly inclined from a position transverse to the bar, each successive adjacent arm being of increasing length with respect to the arm preceding it forwardly and downwardly, to a point substantially at the mid-point of said bar, each successive adjacent arm thence being of decreasing length with respect to the arm 15
- 20 25
